Primary Examiner — Carla Jobe Wright(74) *Attorney, Agent, or Firm* — Stephen J. Weyer, Esq.; Stites & Harbison, PLLC(57) **CLAIM**

The ornamental design for a mobile communications device band, as shown and described.

DESCRIPTION

FIG. 1 is a perspective view taken from the top, front, and left side of the mobile communications device band of the present invention.

FIG. 2 is a perspective view taken from the top, rear, and left side of the mobile communications device band of FIG. 1.

FIG. 3 is a front elevation view of the mobile communications device band of FIG. 1.

FIG. 4 is a rear elevation view of the mobile communications device band of FIG. 1.

FIG. 5 is a left side elevation view of the mobile communications device band of FIG. 1.

FIG. 6 is a right side elevation view of the mobile communications device band of FIG. 1.

FIG. 7 is a top plan view of the mobile communications device band of FIG. 1; and,

FIG. 8 is a bottom plan view of the mobile communications device band of FIG. 1.
